UNITED STATES PATENT OFFICE

JOSEPH MARTIN, OF NEW YORK, N. Y., ASSIGNOR TO UNITED STATES CABINET BED CO., OF BROOKLYN, NEW YORK, A CORPORATION OF NEW YORK

DAY-BED

Application filed February 26, 1930. Serial No. 431,354.

This invention relates to day-beds in general.

Among the objects of the present invention it is aimed to provide an improved day-bed having a frame, an extension bed section and a main bed section, in which the extension bed section is pivotally connected to the frame and operatively connected to the main bed section, so that as the extension bed section is swung into its outer position it will cause the main bed section to be raised and when the extension bed section is swung into its inner position it will cause the main bed section to be lowered to form an enlarged bed compartment between the two bed sections in single bed formation.

These and other features, capabilities and advantages of the invention will appear from the subjoined detail description of one embodiment thereof illustrated in the accompanying drawings in which

Figure 1 is a perspective of a day-bed made according to the present invention in single bed or couch formation;

Fig. 2 is an enlarged end elevation of the day-bed in single bed formation with the end frame removed showing the extension bed section and connected parts in dash and dot lines in the course of being opened;

Fig. 3 is an end elevation of the day-bed in double bed formation with the end boards removed; and

Fig. 4 is a fragmental plan view of the day-bed in double bed formation with the end boards removed.

The day-bed consists essentially of a main frame F which has attached thereto the foot and head boards 1, 2, and the back board 3 of a couch.

The frame F, as illustrated in Figs. 2 and 3, has end frame members 4, each having uprights 5, 6, an upper cross bar 7 and a lower cross bar 8. The uprights 5 and 6 of the end frame members 4 are connected to one another by the board pieces 9 and 10.

Operative to move up and down within the main frame F, there is provided the main bed section A. Operative to move into an extended position or double bed formation and back into single bed formation,

there is provided the extension bed section B.

The main bed section A is provided with end bars 11 which are connected to one another by the elongated side bars 12. Each of the end bars 11 is provided with a slot 13 at one end corresponding to the slot 14 in each of the lower cross bars 8 of the end frame members 4. The main frame A is connected to the lower cross bars 8 by two pairs of levers, each pair consisting of two levers 15 and 16 which are pivotally connected to one another at 17. The lever 15 is pivotally connected at 18 to one end of the end bar 11 and provided with a stud 19 at its lower end traveling in the slot 14. The lever 16, on the other hand, is pivotally connected at 20 to one end of the lower cross bar 8 and provided with a stud 21 at its upper end traveling in the slot 13 of the end bar 11.

The extension bed section B is also provided with end bars 22 which are connected to one another by the elongated side bars 23. The extension bed section B is pivotally connected to the upper ends of the uprights 5 of the end frame members 4 by pins 24, in which case the frame portion 23 adjacent the pins 24 serves as the equalizer so that both ends of the frame will at all times rise at the same time even when only one side of the extension bed section is engaged in the act of manipulating the same.

In order to serve as legs or supports for the extension bed section B when in extended position, each end of the frame B is provided with a leg 25 which is pivotally connected at 26 to the end bar 22 of the frame B and has an upwardly extending portion 27 to the upper end of which there is pivotally connected the link 28 which in turn is pivotally connected to the control link 29. The control link 29 is pivotally connected at 30 to the end bar 22 and pivotally connected at its other end to the stud 21 on the lever 16. Preferably, as indicated, the control link 29 is bent at 31 to clear the pivotal connection of the lever 15 with the end bar 11.

As illustrated in the present instance, the frame portion A has permanently secured to its upper surface a spring mattress 32.

The bed section B, on the other hand, is provided both with an upholstered couch portion 33 to one face thereof and a spring mattress 34 to the other face thereof, the 5 spring mattress 34 being secured to the face of the bed section B which faces downwardly in single bed formation and upwardly in double bed formation, so that, as illustrated in Fig. 3, the spring mattress 34 will be upward in double bed formation and the upholstered portion 33, as illustrated in Fig. 2, will be upward in single bed formation.

To facilitate the action of the levers 15 and 16 when manipulating the bed into 15 single bed and double bed formation, each of the levers 15 are provided with a spring 35 which connects such lever 15 between its pivotal connection 17 and its stud 19 with the lower cross bar 8, as illustrated in Fig. 4.

20 In the operation of this bed, as illustrated in Fig. 3 in double bed formation, the spring mattresses 34 and 32 will be located at the same level and when the bed section B is swung over into single bed formation, the 25 position illustrated in Fig. 2, the cross bars 15 and 16 connected to the control links 29, will actuate the frame A into the lowered position illustrated in Fig. 2, where a decided bed compartment will be formed between the spring mattress 34 and the upper 30 face of the spring mattress 32. During this operation of the bed section B into single bed formation, the connection of the legs 25 with the control links 29 by the links 28 will cause 35 the legs 25 to fold up into the position illustrated in Fig. 2.

It is obvious that various changes and modifications may be made to the details of construction without departing from the general spirit of the invention as set forth in 40 the appended claims.

I claim:

1. The combination with a main frame, 45 of an extensible bed section pivotally connected to said main frame, a main bed section, crossed levers pivotally connected to one another and operatively connecting said main bed section with said main frame, control links pivotally connecting said crossed 50 levers with said extensible bed section whereby said crossed links will be operated to raise said main bed section when said extensible bed section is swung outwardly, legs pivotally connected to said extensible bed section, 55 and links operatively connecting said legs with said control links so that said legs will be swung into supporting position when said extensible bed section is swung outwardly.

2. The combination with a frame, of a 60 main bed section, two pairs of crossed levers, each pair pivotally connected to one another, one lever of each pair pivotally connected to said main bed section and slot and pin connected to said main frame, the other lever of 65 each pair pivotally connected to said main

frame and slot and pin connected to said main bed section, an extensible bed section pivotally connected to said main frame, a control link pivotally connected to each end of said extensible bed section and pivotally connected at its other end to said other lever of said crossed levers, a leg pivotally connected to each end of said extensible bed section, and a link pivotally connected to each leg at one end and at its other end pivotally connected to one of said control links.

JOSEPH MARTIN.
